UNITED STATES PATENT OFFICE.

ZEDDIE LEE HARBIN, OF GASTONIA, NORTH CAROLINA, ASSIGNOR OF ONE-HALF TO
EMANUEL FROHMAN, OF GASTONIA, NORTH CAROLINA.

CHURN.

Application filed February 26, 1926. Serial No. 90,879.

This invention relates to churns embodying among other characteristics a dasher arm carrying agitator members disposed in different directions to thoroughly mix and 5 agitate the contents of the churn.

Another object of my invention resides in the provision of an operating mechanism connected with the dasher arm to impart the necessary momentum to the dasher arm and 10 agitators.

With the above and other objects in view, the invention further includes the following novel features and details of construction, to be hereinafter more fully described, illustrated in the accompanying drawings and pointed out in the appended claims.

In the drawings:—

Figure 1 is a vertical sectional view taken through the invention.

20 Figure 2 is a rear elevation thereof.

Figure 3 is a sectional view taken on line 3—3 of Figure 1.

Figure 4 is a sectional view taken through the closure cover and removable portion 25 thereof.

Referring to the drawings in detail, wherein like characters of reference denote corresponding parts, the reference character 10 indicates a rectangular frame formed by 30 angle bars 11 and having legs 12 secured to the under sides of their corners while the upper sides form a seat for the lower edges of a can 13 having a closure lid 14 arranged upon the periphery thereof. A frustro-conical shaped cutout portion 15 being provided within one side and extending to the center of the closure lid 14 and providing shoulders 16 upon the opposite side edges thereof for supporting the corresponding 35 shoulders of a frustro-conical shaped strip 17 having a knob 18 secured to its upper side to permit its removal when desired. Pairs of relatively flat supporting arms 19 having their lower ends secured to the corners of 40 the frame 10 while their opposite upper ends extending inwardly and twisted upon themselves and providing spaced parallel ends 20 within which the opposite ends of a plate 21 is secured. The said plate 21 having an 45 L-shaped cutout portion 22 provided therein, the purpose of which will be presently apparent. A driving shaft 23 extending through one pair of the ends 20, the plate 21, and the vertical portion of the substan-

tially L-shaped cutout portion 22 and having 55 a pinion 24 secured thereto while its opposite end having a correspondingly secured fly wheel thereon including an eccentrically mounted operating handle 26. A spur gear 27 and gear 28 being mounted within the 60 horizontal portion of the cutout portion 22 and meshing with each other while the spur gear having its swiveled portion meshing with the pinion 24 in order that location of the fly wheel will impart like movement to the 65 gear 28 having an enlarged adjustable sleeve or socket 29 extending downwardly therefrom at an appreciable distance above the closure lid of the can 13. A dasher arm 30 having its upper end fitted within the enlarged socket end 29 protruding from the gear 28 and within the frustro-conical shaped opening 15 in the closure lid 14 and providing downwardly and upwardly extending oppositely disposed semi-circular 70 dasher arms 31 upon their lower ends which extend in slight spaced relation with respect to the bottom of the can 13.

It will thus be noted from the foregoing description and accompanying drawing that 75 the dasher arms 31 may be rotated within the can 13 upon the rotation of the fly wheel 25 when clasping the eccentrically mounted handle 26.

In order to provide a foot pedal arrangement for use in conjunction with the fly wheel 25 I provide an operating rod 32 forming a loop 33 upon its upper end encircling an appropriate portion of the eccentrically mounted handle 26 while its 80 lower end being pivotally mounted between spaced parallel ears 34 provided upon the foot end of the foot pedal 35 which in turn having apertured ears 36 provided upon its under side for pivotally locking movement 85 between corresponding ears 37 mounted upon the upper side of a platform 38 but being pivotally associated as indicated at 39 to one side of the frame 10 and including supporting legs 40 upon its opposite ends. 90 A retractile spring 41 being secured to the upper side of the platform 38 and having its opposite end secured to the under side and adjacent the foot end of the foot pedal 35 in order that the said operating arm or rod 95 100 105 32 and foot pedal 35 will be normally positioned as clearly illustrated in Figure 1 of the drawing.

It is further to be noted that when it is desirous of removing the can 13 from the frame 10, the dasher arm 30 is released from the adjustable socket 29 which will then drop down within the can 13 through the closure lid 14 whereby the can as a whole may be readily and easily removed. Obviously the closure lid 14 may be removed from the periphery of the frame 10 independently of the dasher arm 30 upon the removal of the frusto-conical shaped closure lid 17.

The invention is susceptible of various changes in its form, proportions and minor details of construction, and the right is here-

in reserved to make such changes as properly fall within the scope of the appended claim.

Having thus described the invention, what is claimed is:—

In a device of the character described comprising a can, a dasher arm suspended therein, an enlarged portion carried upon one end of the arm, and semi-circular oppositely disposed dasher arms arranged in superimposed relation and having their points of intersection disposed wholly within the enlarged portion.

In testimony whereof I affix my signature.

ZEDDIE L. HARBIN.
